UNITED STATES PATENT OFFICE.

ALBERT M. THOMPSON, OF CHICAGO, ILLINOIS.

AUTOMATIC TRAIN-CONTROL SYSTEM.

Application filed February 19, 1921. Serial No. 446,291.

To all whom it may concern:

Be it known that I, ALBERT M. THOMPSON, a citizen of the United States, residing at Chicago, in the county of Cook and State 5 of Illinois, have invented new and useful Improvements in Automatic Train-Control Systems, of which the following is a specification.

This invention relates to automatic train control systems of the electric type designed to eliminate accidents in railway travel and an object of the invention is to provide a system which is positive in action and will automatically stop a train by applying the 15 brakes when it reaches the danger zone relative to a second train.

Another object of the invention is the construction and arrangement of apparatus in circuits in such manner that a high voltage 20 current will always be established to overcome high resistance under danger conditions to render active the apparatus for closing the throttle lever and applying the air brakes of a train.

25 Another object of the invention is to provide electrical means moving a predetermined distance for stopping the train and locking the mechanism in this position as long as danger conditions exist so that the 30 mechanism can not be returned to safety position by the engineer until danger conditions have passed.

A further object of this invention is to provide means automatically operated at a 35 predetermined time for arresting operation of a control motor.

Another object of the invention is the arrangement and connection of apparatus whereby high-frequency current is maintained at all times and to direct the flow of 40 said high-frequency current in a direction to actuate train stopping mechanism upon a train entering a danger block.

Other objects of the invention will appear 45 in the following detailed description and in the accompanying drawings wherein:

Fig. 1 is a wiring diagram of the entire system.

Fig. 2 is a front elevation of the cab car- 50 ried instruments.

Fig. 3 is a diagrammatic view illustrating one manner of operating the throttle lever and the air brake valve.

Again referring to the drawing illustrat- 55 ing in a diagrammatic manner one construc- tion of my invention the numeral 1 design-

nates a trackway divided into the usual blocks A, B and C. For the purpose of illustration the letter A designates "advance" block, the letter B "danger" block, 60 and the letter C "caution" block.

The numeral 2 designates the usual track battery supplying current in the usual manner to the semaphore signal and also supplying current to a partial track circuit 3 including the solenoid 4. From this construction it will be seen that when the axle F bridges the rails of a block, current will be short circuited from battery 2 to the partial circuit 3 thereby deenergizing solenoid 4 allowing the core or plunger 5 to gravitate. The numeral 6 designates the third rail section of the proper length and arranged at the entrance of each block and heavily insulated from the ground. Attention is called to the fact that the third rail 6 is of a length to continue to cooperate with rod 17 after the train has been stopped. A lever 7 is pivotally mounted and has a connection with the plunger 5 so that when the solenoid is de-energized the lever will swing into engagement with a portion of the rail section 6 and as the lever is grounded, as illustrated at 8, current may readily pass from the rail section to the ground. 80 The solenoid, lever, and stem 9 are arranged in a suitable housing so as to be protected from the elements and thereby assure proper electrical connections at all times.

The train carrying mechanism now to be 90 described consists of an induction coil 10, the primary winding 11 of which is arranged in a primary circuit 12 including a current generator shown at 13. The secondary winding 14 is arranged in a secondary 95 circuit 15 that has one terminal grounded upon the train as indicated at 16 and its other terminal connected to a rod 17 that is positioned upon the locomotive to pass directly over the third rail section 6. Included in the circuit 15 is a main control magnet 19 and a double throw switch 20.

A circuit 21 has its terminals connected to two of the contacts 22 of the double throw switch and has in circuit therewith an auxiliary control magnet 23. From this arrangement it will be seen that by throwing the switch 20, magnet 19 will be cut out of circuit and magnet 23 thrust into circuit. It will also be noted that by continuously 110 driving the generator 13 current will pass continuously through the primary coil

which will induce high voltage in the secondary coil 13 with the result that when the third rail 6 is grounded in the manner heretofore stated current will pass from the 5 rod 17 to the rail 6 and to ground establishing a flow of current through the magnet 19 for controlling operation of suitable instruments hereinafter described. Magnet 19 controls closing of the switch 24 arranged 10 in a motor circuit 25 that includes a motor 26 and a source of current 27. The signal 28 is bridged across this circuit.

Referring more particularly to Fig. 2 the motor 26 is provided with smaller gear 29 15 meshing with a larger gear 30 which, in turn, is keyed to a shaft 31 carrying a pitman wheel 32. A pitman 33 connects the wheel 32 to a lever 34 that is keyed to a shaft 35. This lever 34 has a link connection 36 with the lever 37 that is connected by a link 38 to a stem 39 of an air valve 40. This air valve 40 is so arranged that when open, air will pass from the train line 20 through the pipe 41 to the air motors 42 and 43 that are illustrated in a diagrammatic manner in Figure 3. These air motors have a connection 44 with the throttle lever 45 and handle 46 of the usual air brake valve. Keyed to the shaft 35 is a ratchet 30 47 with which co-operates the pawl 48, that is under control of the magnet 23. The numeral 49 designates a brake band co-operating with the wheel 32 to limit rotation 25 of the wheel and this brake band which may 35 be of any well known construction, is operated by electromagnet 50 arranged in the circuit 51 which includes a spring operated switch 52 and the battery 53. The numeral 54 designates a pair of normally spaced contacts that control the continuity of circuit 40 51 and are so tensioned as to automatically move into engagement with each other upon predetermined movement of the lever 37 as clearly shown in Fig. 2; in other words, 45 when the lever 37 moves to position corresponding to an open position of the valve 40 the contacts will engage for operating the magnet 50 for braking further movement of the lever 32. Arranged in the path 50 of movement of the lever 34 is any suitable form of indicator shown diagrammatically at 55. The stem 56 of this indicator is arranged to be operated when the lever 34 is fully thrown.

55 The apparatus just described is arranged in a box 57 having a hinged lid 58 which is sealed when the train leaves the terminal.

When a train is in block A as indicated by the wheels 5 magnet 4 is rendered inactive 60 which allows the lever 7 to ground rail 6. A train entering block B will cause the rod 17 to slide over the rail 6, and as rail 6 is grounded, current will flow through the secondary circuit energizing magnet 19 and 65 closing the motor circuit. Motor 26, upon

operating, shifts the mechanism in the box 57 for opening the valve and allowing the operation of the air motors to stop the train. After the mechanism has been properly operated the required distance the 70 brake circuit is closed which renders the brake band 49 active. As long as a train is in block A current will continue to flow through magnet 19 thereby continuing a flow of current through motor 26; to prevent this 75 loss of current the circuit to magnet 19 can be interrupted by opening the switch 20 which throws same into engagement with contacts 22 and thereby closes the circuit 21 rendering magnet 23 active. Magnet 23 at 80 attracts pawl 48 into engagement with the ratchet 47 and prevents the engineer from restoring the mechanism to normal position thereby allowing air pressure to act upon the motors and hold the throttle lever and 85 air brake handle in stopping position. As soon as the train 5F leaves block A the solenoid 4 is again active which retracts the lever 7 from rail 6 and thereby the ground is destroyed and current is prevented from passing through the partial 90 circuit 21 and thus the pawl 48 gravitates out of engagement with the ratchet 47 and allows the engineer to restore the parts. Due to the arrangement of the recorder 95 same will operate each time the train is automatically brought to a stop by my improved mechanism, thereby making a permanent record.

It is, of course, to be understood that to 100 release the brake the circuit 51 is interrupted by manually opening the switch 52 which will be automatically moved to closed position when released, due to the fact that same is spring operated. At this point I 105 wish to call attention to the fact that the air motors may be of any of the usual construction heretofore designed and therefore, the air motors are only shown in a diagrammatic manner.

It is, of course, to be understood that the various instruments may be constructed in various other manners than illustrated and may be electrically associated in other relations and, therefore, I do not desire to be 110 limited in any manner except as set forth in the claims hereunto appended.

Having thus described my invention what I claim is:

1. In an automatic train control, a control lever, electrical means for operating the lever, means operated by movement of the lever for arresting operation of its operating means, means for locking said lever in operated position, and electrical means for 115 releasing said locking means.
2. An automatic train control system comprising, a primary circuit including a primary winding, a secondary circuit including a secondary winding operatively asso- 130

ciated with said primary winding, electrical means for closing the throttle lever and operating the air-brake system of a train, and locking means therefor, both of said means 5 being operatively associated with said secondary circuit.

3. An automatic train control system comprising, a normally open high voltage circuit adapted to be closed under danger conditions, means for cutting off motive power of 10 a train electrically associated with said circuit, and means for interrupting said circuit and locking said means against return to normal position.

15 4. An automatic train control system comprising, a normally open high voltage circuit adapted to be closed under danger conditions, means for cutting off motive power of a train electrically associated with said 20 circuit, and means for rendering said first means inactive and locking same against return to normal position as long as danger conditions exist and to immediately release said means under safe conditions.

25 5. In an automatic train control, a control lever, electrical means for operating said control lever, a track solenoid, means operated by energizing of said track solenoid to permit operation of said control lever operating 30 means, means for locking said control lever in an operated position, electrical means for releasing said locking means, and means operated during movement of the lever to arrest operation of the lever operating means.

6. In an automatic train control system, an engine carried generator, a primary circuit connected thereto, a secondary circuit, a control lever, electrical means for operating 40 said control lever, means in said secondary circuit for controlling operation of said lever operating means, a double throw switch bridged in said secondary circuit, means for locking said control lever in operated 45 position, and electrical means controlled by operation of said switch for releasing said locking means.

7. In an automatic train control system, an engine carried generator, a primary circuit 50 connected thereto, a secondary circuit, a control lever, electrical means for operating said control lever, means in said secondary circuit for controlling operation of said lever operating means, a double throw switch bridged in said secondary circuit, means for locking said control lever in operated 55 position, electrical means controlled by operation of said switch for releasing said locking means, and means operated during movement of said lever to arrest 60 operation of the lever operating means.

8. In an automatic train control system, an engine carried generator, a primary circuit connected thereto, a secondary circuit, 65 a control lever, electrical means for operat-

ing said control lever, means in said secondary circuit for controlling operation of said lever operating means, a double throw switch bridged in said secondary circuit, means for locking said control lever in operated 70 position, electrical means controlled by operation of said switch for releasing said locking means, means operated during movement of said lever to arrest operation of the lever operating means, and a register adapted to be operated upon each operating movement of said control lever.

9. In an automatic train control system, an engine carried generator, a primary circuit connected thereto, a secondary circuit, 80 a control lever, electrical means for operating said control lever, means in said secondary circuit for controlling operation of said lever operating means, a track carried solenoid, means operated by energizing of 85 said track solenoid for controlling exciting of said lever operating means, a double throw switch bridged in said secondary circuit, means for locking said control lever in operated position, and electrical means controlled by operation of said switch for releasing 90 said locking means.

10. In an automatic train control, a control lever, a motor, a pitman geared to said motor and connected to said lever for operating the lever upon operation of the motor, a brake for arresting rotation of said pitman gear, electrical means for operating said 95 brake, and means operated by movement of said control lever for controlling energizing 100 of said electrical means.

11. In an automatic train control, a control lever, a motor, a pitman geared to said motor and connected to said lever for operating the lever upon operation of the motor, a brake band for arresting rotation of said pitman gear, a solenoid for applying said 105 brake band to the gear, and a circuit closer operated by operation of said control lever for controlling energizing of said solenoid. 110

12. In an automatic train control, a control lever, a motor, a pitman geared to said motor and connected to said lever for operating the lever upon operation of the motor, a ratchet carried by said lever, and an electrically operated pawl for engagement with said ratchet to lock said control lever in an operated position. 115

13. In an automatic train control, a control lever, a motor, a pitman geared to said motor and connected to said lever for operating the lever upon operation of the motor, a ratchet carried by said lever, a pawl for engagement with said ratchet to lock said control lever in an operated position, a solenoid for operating said pawl to release said lever for movement, and manually operated means for controlling energizing of said solenoid. 120

14. In an automatic train control system, 130

- an engine carried generator a primary circuit connected thereto, a secondary circuit, a control lever, electrical means for operating said control lever, means in said secondary 5 circuit for controlling operation of said lever operating means, a double throw switch bridged in said secondary circuit, means for locking said control lever in operated position, electrical means controlled by operation 10 of said switch for releasing said locking means, and means operated during movement of said lever to arrest operation of the lever operating means, and a signal bridged in the control circuit of said control lever 15 operating means.
15. In an automatic train control, a control lever, a motor, a pitman geared to said motor and connected to said lever for operating the lever upon operation of the motor, 20 a brake for arresting rotation of said pitman gear, electrical means for operating said brake, means operated by movement of said control lever for controlling energizing of said electrical means, and a signal bridged 25 in the control circuit of said control lever operating means.
16. An automatic train control system

comprising a primary circuit, a secondary circuit closed under danger conditions, a control magnet in the secondary circuit, a 30 motor circuit under control of said magnet, mechanism operated by the motor for applying the air brakes in closing the throttle of a train, means for cutting said magnet out of circuit, and control means rendered operative upon action of said first means for preventing restarting of said mechanism to normal position when danger conditions exist.

17. An automatic train control system 40 comprising a primary circuit including a generator, a secondary circuit rendered complete under danger conditions, a motor circuit closed upon closing of said secondary circuit, control means for regulating the 45 operation of said motor, control mechanism having a drive connection with said motor, and a locking device manually operated for preventing the return movement of the mechanism to normal position when danger 50 conditions exist.

In testimony whereof I affix my signature.

ALBERT M. THOMPSON.
